UNITED STATES PATENT OFFICE.

EDWIN E. SLICK, OF PITTSBURGH, PENNSYLVANIA.

METHOD OF AND APPARATUS FOR FORGING CAR-WHEELS.

1,108,260.

Specification of Letters Patent. Patented Aug. 25, 1914.

Application filed April 5, 1910. Serial No. 553,599.

To all whom it may concern:

Be it known that I, EDWIN E. SLICK, of Pittsburgh, in the county of Allegheny and State of Pennsylvania, have invented a new and useful Method of and Apparatus for Forging Car-Wheels, of which the following is a full, clear, and exact description, reference being had to the accompanying drawings, forming part of this specification.

- 10 My invention relates to the manufacture of rolled metal car wheels and to apparatus for manufacturing such wheels. Heretofore, it has been proposed to roll such wheels on a forming die by means of forming rollers in which the faces of the forming die are normal to the axes of rotation of the die and wheel, and extend outwardly from the axial center to the periphery of the blank. This results in the metal being displaced unevenly 15 in different annular portions of the blank being formed and slippage between the surfaces of the wheel and of the die or forming rolls, causing rapid wear of the forming die surfaces.
- 20 The object of my invention is to provide a novel method of displacing the metal in forming the wheels and apparatus having improved means by which the metal in different annular portions of the wheel blanks 25 is reduced in cross section and is caused to flow at substantially the same surface speed.

A further object of the invention is to provide apparatus of improved construction adapted for use in roller forging the metal 30 blanks into car wheels in accordance with my improved method.

To that end the invention consists in rolling the blanks between forming faces which extend at an angle to the axis of the wheel, 35 supporting die and rolls, in such manner that the blank is rolled and formed in the cavities of a frusto-conical forming die by means of forming rolls.

Referring to the drawings, Figure 1 is a 40 plan partly in section, showing apparatus constructed and arranged in accordance with my invention. Fig. 2 is a side elevation partly in section of the same. Fig. 3 is a 45 detail plan showing a portion of the apparatus, the rotary supporting die being shown in section. Fig. 4 is a sectional plan showing the construction of the spindles for the forming rolls and the bearings in which they 50 are carried, and the means employed for adjusting the forming rolls toward and away 55 from the axes of the wheel blank and sup-

porting die. Fig. 5 is a sectional side elevation on the line V—V of Fig. 4, showing the manner in which the blank is held in position on the forming die during the forming 60 operation. Fig. 6 is a sectional elevation showing reciprocating dies used in flattening or bending the wheels after the completion of the forging operation.

In the drawings, 2 designates a recessed 65 supporting die on which the blanks are supported while being forged. The die 2 is removably secured to the flange 3 of the shaft or spindle 4. The shaft 4 is carried in a roller bearing 5 and roller thrust bearing 6 70 on the base plate 7 of the machine, the end of this shaft being provided with a wobbler 7^a to which a driving spindle is connected by a coupling box (not shown) and through which the die 2 is rotated. The coupling box 75 and spindle construction being old and well known need not be further described. Also mounted upon the base plate 7 is a reciprocating carrier 8 which is arranged to be moved toward the forming die 2 by means 80 of the plunger 9 mounted in the hydraulic cylinder 10. The pull back cylinder 11 in which the plunger 12 is mounted is connected by means of the rods 13 with the carrier 8 on the base plate 7 of the apparatus and 85 is mounted so as to be carried by the support 14 when the carrier 8 is moved toward and away from the forming die 2.

Rotatably mounted in the carrier 8 is a plunger or shaft 15 forming a stop, the 90 outer end of which extends into proximity to the face of the die 2 for a purpose described hereinafter.

Mounted upon the carrier 8 in roller thrust bearings 17 and 18, are the wheel forming 95 rolls 19 and 20. The roll 19 with its bearing 17 is arranged to be adjusted axially toward and away from the axis of the forming die 2 by means of the adjusting screw 21, the roll being held in its adjusted position by 100 means of the lock nut 22. The roll 20 with its bearing 18 is adjusted toward and away from the axis of the forming die 2 in a similar manner by means of the adjusting screw 23, the screw being held in its adjusted positions by the lock nut 24. As shown in the drawings, the forging or forming rolls 19 and 20 are arranged to rotate by frictional contact with the blank being formed.

The forming die 2 is preferably provided 110 with an axially central opening in which a centering pin 25 is placed at the beginning of

the forging operation, to maintain the blank in its centered position during such forging operation.

- In the operation of the apparatus in carrying out my improved method, the blank A is placed in position on the centering pin 25 as is best shown in Fig. 3. The die 2 is then rotated by any suitable type of motor, which is connected to the die through the wobbler 10 on the end of the shaft 4. Fluid pressure is then admitted to the hydraulic cylinder 10 and the carrier 8 is advanced so that the forming roll 19 is brought into engagement with and begins the forging operation of the blank A. As the carrier 8 and the forming rolls 19 and 20 are farther advanced toward the die tool, the blank is gradually shaped and caused to conform to the contour of the cavities in the recessed die 2, the diameter of the blank being increased by this operation. When the blank has been reduced in thickness to the desired extent, the forming roll 20 comes into engagement with the periphery of the blank and, together with the co-acting faces of the supporting die 2, forms the flange and tread portions of the wheel to the desired contour. The metal in the center of the blank, as shown in Fig. 3, is displaced to form the hub and the adjacent portion of the web, the opening through the blank being practically complete at the end of the forging operation, and in the condition shown in Fig. 5. Either the adjacent ends of the stop 15 and the pin 25 are in engagement, or possibly a thin fin of metal will remain between the adjacent ends of the pin 25 and stop 15. The tendency of the forming rolls is to pull the metal away from the axial center of the blank during the forging operations. As the carrier 8 is moved toward the die 2 the end of the stop 15 comes into engagement with the opposite face of the blank 8 and prevents the metal in the hub portion of the wheel blank being displaced outwardly beyond the desired amount. When the carrier 8 is moved into the position with reference to the die 2 as shown in Fig. 4, and the wheel forming operation has been completed, the fluid pressure on the cylinder 10 is then shut off and fluid pressure applied to the pull-back cylinder 11, which operation causes the carrier 8 to retract and move away from the die 2. The wheel so formed is then removed from the die 2 and a new blank is put in position, when the above described operations are repeated.
- It will be noted that the surface of the forming die is substantially conical and that the forming roll 19 is also conical. By means of this construction the surface speed in any transverse plane on the conical forming rolls is substantially the same as the intersecting portion of the conical face on the supporting roll. This arrangement of the co-operating conical faces causes a uniform

surface speed of the die, blank and forming roll during the forging operation, and substantially eliminates slippage between the faces of the forming roll or die and the blank. This feature is of very great importance, such slippage being the reason for the failure of a large number of proposed methods of roller forging car wheels.

The wheel as completed in the forging operation may be formed with the hub in the desired relation axially with the flange and tread portions. It also may not be formed with the hub in the desired relation axially with the flange and tread portions and in such cases the forged wheels, after being removed from the die 2 are placed between reciprocating forming dies 26 and 27, as is shown in Fig. 6 and the wheel is bent or flattened so as to bring the faces of the different portions of the wheel into the desired axial relation with one another. After this operation is completed the wheel is bored to a wheel fit and when found necessary or desirable its flange and tread may be turned to the desired diameter.

The advantages of my invention will be apparent to those skilled in the art. The apparatus is simple and by its use the amount of slippage between the co-acting forming faces and the blank is reduced to a minimum.

Modifications in the construction and arrangement of the parts may be made without departing from my invention as defined in the claims.

I claim:—

1. The method of forming metal consisting in subjecting a metal blank to forging pressure between the co-acting faces of a supporting die and a rotating forming roll and applying the forging pressure to at least part of said blank at an oblique angle to the axes of said die and roll; substantially as described.

2. The method of forming metal consisting in subjecting a metal blank to forging pressure between the co-acting faces of a supporting die and a rotating forming roll, applying the forging pressure to at least part of said blank at an oblique angle to the axes of said die and roll and then bending the forged blank to the desired cross sectional contour; substantially as described.

3. The method of forming metal consisting in subjecting a metal blank to forging pressure between the co-acting faces of a rotating supporting die and a rotating forming roll and applying the forging pressure to at least part of said blank at an oblique angle to the axes of said die and roll; substantially as described.

4. Apparatus for forging comprising a rotary supporting die, a forming roll co-acting therewith in forging the metal, means for rotating said die and means for causing

a relative approach of the forming faces of said die and roll, at least part of the forming faces of the die and roll being inclined respectively to the axes thereof; substantially as described.

5. Apparatus for forging metal comprising a supporting die, a forming roll, at least part of the co-acting forming faces of said die and roll being inclined respectively to the axes thereof, means for causing a relative rotary movement of the die and roll and means for causing a relative approach of the forming faces of said die and roll; substantially as described.

10. 6. Apparatus for forging metal comprising a rotary supporting die, a forming roll, the co-acting forming faces of said die and roll being inclined respectively to the axes thereof, means for positively rotating said die, means for causing a relative approach

of the forming faces on said die and roll, and means for adjusting said forming roll axially; substantially as described.

7. Apparatus for forging metal comprising a rotary supporting die, a forming roll, 25 the co-acting forming faces of said die and roll being inclined respectively to the axes thereof, means for positively rotating said die, means for causing a relative approach of the forming faces on said die and roll, 30 means for adjusting said forming roll axially and a stop arranged to prevent axial movement of the blank on the die; substantially as described.

In testimony whereof, I have hereunto set 35 my hand.

EDWIN E. SLICK.
